UNITED STATES PATENT OFFICE.

HOMER W. CASE, OF PITTSBURGH, PENNSYLVANIA, ASSIGNOR TO PITTSBURGH TOY VEHICLE COMPANY, OF PITTSBURGH, PENNSYLVANIA.

DESIGN FOR A VELOCIPED FOR THE USE OF CHILDREN.

50,882.

Specification for Design.

Patented June 5, 1917.

Application filed January 16, 1917. Serial No. 142,769. Term of patent 3½ years.

To all whom it may concern:

Be it known that I, HOMER W. CASE, a citizen of the United States, residing at Pittsburgh, in the county of Allegheny and State of Pennsylvania, have invented a new, original, and ornamental Design for Velocipedes for the Use of Children, of which the following is a specification.

Referring to the drawing, forming a portion of this specification:

Figure 1 is a perspective view of a velocipede for the use of children, showing my new design.

Fig. 2 is a side elevation of a portion thereof.

I claim:

The ornamental design for a velocipede for the use of children, as shown.

In testimony whereof I affix my signature in the presence of two witnesses.

HOMER W. CASE.

Witnesses:

JENNIE JONES,
R. CLEMENT WEBER.
